UNITED STATES PATENT OFFICE.

NATHANIEL L. RIPLEY, OF BOSTON, MASSACHUSETTS.

DESIGN FOR A JEWEL-SETTING.

SPECIFICATION forming part of Design No. 20,025, dated July 15, 1890.

Application filed May 8, 1890. Serial No. 351,086. Term of patent 3½ years.

To all whom it may concern:

Be it known that I, NATHANIEL L. RIPLEY, a citizen of the United States, residing at Boston, in the county of Suffolk and State of Massachusetts, have invented and produced a new and Original Design for Jewel-Settings, of which the following is a specification, reference being had to the accompanying drawings, forming a part thereof.

10 Figure 1 of the drawings represents in side elevation a jewel-setting showing my design. Fig. 2 is a plan view of the same.

15 The leading feature of my design consists in arranging the jewel-setting arms in elevation above a scalloped base, and also in arranging facets between the jewel-setting arms.

20 *a* represents a scalloped base.
b represents arms for holding the jewel.
c represents facets arranged on the scalloped base alternately with relation to the arms *b*.

The facets *c* are herein shown as elliptical. The arms *b* are broadened at the base, at which point they are attached to the facets, and at a point midway said broadened base a downwardly and outwardly extended projection *d* is shown. This projection, arranged as shown, has the appearance of another facet.

I claim—

25 The design for a jewel-setting, substantially as shown.

30 In testimony whereof I have signed my name to this specification in the presence of two subscribing witnesses.

NATHANIEL L. RIPLEY.

Witnesses:

BERNICE J. NOYES,
FREDERICK L. EMERY.
